US0D1112081S

(12) **United States Design Patent** (10) **Patent No.:** **US D1,112,081 S**
(45) **Date of Patent:** **** Feb. 10, 2026**

(54) **CONNECTOR**

(71) Applicant: **BIZLINK INTERNATIONAL CORP.**,
New Taipei (TW)

(72) Inventors: **Yanping Zhang**, New Taipei (TW);
Qixing Xu, New Taipei (TW); **Haoran Zou**, New Taipei (TW)

(73) Assignee: **BIZLINK INTERNATIONAL CORP.**,
New Taipei (TW)

(**) Term: **15 Years**

(21) Appl. No.: **29/899,252**

(22) Filed: **Aug. 7, 2023**

(51) **LOC (15) Cl.** **13-03**

(52) **U.S. Cl.**

USPC **D13/133**

(57) **CLAIM**

The ornamental design for a connector as shown and described.

DESCRIPTION

FIG. 1 is a perspective view of a connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIGS. 1-7 depict portions of the connector that form no part of the claimed design.

1 Claim, 7 Drawing Sheets
